Primary Examiner—Lou Zarfas*Assistant Examiner*—I. Simmons*Attorney, Agent, or Firm*—Richard C. Litman[57] **CLAIM**

The ornamental design for an I.V. needle insertion guide, as shown and described.

DESCRIPTION

FIG. 1 is an environmental perspective view of an I.V. needle insertion guide showing my new design;

FIG. 2 is a front elevational view thereof;

FIG. 3 is a rear elevational view thereof;

FIG. 4 is a top plan view thereof;

FIG. 5 is a left side elevational view thereof, with the right side being a mirror image; and,

FIG. 6 is a bottom plan view thereof.

The broken line showing in FIG. 1 of a hand and tourniquet band is for illustrative purposes only and forms no part of the claimed design.

FIG. 2

FIG. 3

FIG. 5

FIG. 4

FIG. 6
